UNITED STATES PATENT OFFICE

100,039

DESIGN FOR A COCKTAIL DRINKING GLASS

Joll Perry, New York, N. Y.

Application April 18, 1936, Serial No. 62,196

Term of patent 3½ years

To all whom it may concern:

Be it known that I, Joll Perry, a citizen of the United States, residing at New York, in the county of New York and State of New York, have invented a new, original, and ornamental Design for a Cocktail Drinking Glass, of which the following is a specification, reference being had to the accompanying drawing forming part thereof.

The figure is a perspective view of a cocktail drinking glass, showing my new design.

I claim:

The ornamental design for a cocktail drinking glass, as shown.

JOLL PERRY.
